Primary Examiner — Garth Rademaker*Assistant Examiner* — Christopher J Matthews(74) *Attorney, Agent, or Firm* — Price Heneveld LLP(57) **CLAIM**

I claim the ornamental design for a table leg, as shown and described.

DESCRIPTION

FIG. 1 is a front perspective view of a table leg embodying the present invention;

FIG. 2 is a front elevational view of the table leg;

FIG. 3 is a first side elevational view of the table leg;

FIG. 4 is a rear perspective view of the table leg;

FIG. 5 is a second side elevational view of the table leg;

FIG. 6 is a top plan view of the table leg; and,

FIG. 7 is a bottom plan view of the table leg.

The broken lines show portions of the article that form no part of the claim.
